No. 712,208.

Patented Oct. 28, 1902.

P. C. SOUTHWICK.

BALING PRESS.

(Application filed Nov. 26, 1901.)

(No Model.)

UNITED STATES PATENT OFFICE.

PLIN C. SOUTHWICK, OF SANDWICH, ILLINOIS.

BALING-PRESS.

SPECIFICATION forming part of Letters Patent No. 712,208, dated October 28, 1902.

Application filed November 26, 1901. Serial No. 83,796. (No model.)

To all whom it may concern:

Be it known that I, PLIN C. SOUTHWICK, a citizen of the United States, and a resident of Sandwich, county of Dekalb, and State of Illinois, have invented certain new and useful Improvements in Baling-Presses, of which the following is a specification, and which are illustrated in the accompanying drawings, forming a part thereof.

10 The invention relates to baling-presses in which power is applied for advancing the compressing-plunger through the medium of a toggle-joint.

In the machine shown and herein described 15 there is present the common form of oscillating feeder for forcing the charge into the compression-chamber upon the recession of the plunger, the invention consisting in so connecting the feeder with the compressing mechanism that the recoil of the latter is cushioned 20 by the feeding action.

The invention comprises the arrangement and combination of parts hereinafter fully described, and particularly designated in the 25 claims, and which are illustrated in the accompanying drawings, in which—

Figure 1 is a side elevation of a portion of a baling-press, showing the packer and its connection with the operating mechanism. 30 Fig. 2 is a plan view of the same. Fig. 3 is a detail side elevation of the packer, and Fig. 4 is an end view of the same.

In the drawings there is illustrated the common form of chamber-body 9, having a top 35 feed-opening; the reciprocating compressing-plunger 10; a shaft 13, having keyed thereto and oscillating above the same a member 11, to which is connected the other member, 12, of the toggle for operating the plunger, the member 11 and the end of the member 12 oscillating over the shaft during the operation of the 40 press; the chain 14, secured to one of the toggle members and turning about a sheave 15, by means of which power is applied for straightening the toggle; the chain 16, secured to a cam-crank 17, fixed to the shaft 13 and turning about the sheave 18, by means of which the compressing-plunger may be 45 positively withdrawn, and the feeder-arm 21, carried by a rock-shaft 19, journaled across the top of the body 9 just back of its feed-opening, the feed-arm carrying the plates 22

23 for forcing the material into the compression-chamber.

A crank-arm 24 is fixed upon the shaft 19 55 and a crank-arm 26 upon the shaft 13, and a rigid pitman 25 connects the two crank-arms. These arms are so disposed angularly that when the compressing-plunger is retracted the feed-arm is advanced. As in the machine 60 shown the shaft 13 turns approximately half around, while the shaft 19 makes but approximately a quarter-turn, the crank-arm 26 is considerably shorter than the arm 24.

A plate 27 projects backwardly from the 65 top of the plunger, as usual, and as the latter advances a new charge of material is thrown upon this plate. Upon the recession of the plunger the feeder descends and forces the new charge into the compression-chamber 70 and is carried down thereupon positively by the crank-and-pitman connections referred to, so that the resistance of the material is borne back to and sustained by the toggle and in opposition to the force retracting the 75 same.

In machines of this type when the shorter member 11 of the toggle passes the perpendicular on recession it falls back heavily, to the detriment of the mechanism. Cushioning-springs have heretofore been depended upon to take up this strain; but by the construction here shown and described these springs are dispensed with and the elasticity of the material itself affords the necessary 80 cushioning action, while the positive application of power to the feeder insures the packing of the charge well down into the compression-chamber.

I claim as my invention—

1. In a baling-press, in combination, a plunger, a rocker-shaft, a toggle connecting the rocker-shaft and the plunger, one member thereof being a crank-arm of the shaft and oscillating over the shaft, a chain or cable 95 for receding the toggle, an oscillating feeder having a crank-arm, a crank-arm on the rocker-shaft, and a pitman connecting said two last-mentioned crank-arms, the parts being so disposed that the feeder is advanced 100 as the toggle recedes.

2. In a baling-press, in combination, a baling-chamber, a plunger reciprocating therein, a rocker-shaft, a toggle-joint connecting the

plunger and the rocker-shaft, one member thereof being keyed to and oscillating above the shaft, an oscillating feeder, a crank-arm keyed upon the rocker-shaft, a crank-arm for 5 actuating the feeder, and a pitman connecting the two crank-arms, the two crank-arms and the toggle member attached to the rocker-

shaft being so disposed that the feeder advances as the plunger recedes.

PLIN C. SOUTHWICK.
